UNITED STATES PATENT OFFICE.

EDWARD A. JOHNSTON, OF CHICAGO, ILLINOIS, ASSIGNOR TO MCCORMICK HARVESTING MACHINE COMPANY, OF CHICAGO, ILLINOIS.

SELF-BINDER.

SPECIFICATION forming part of Letters Patent No. 690,964, dated January 14, 1902.

Application filed March 5, 1901. Serial No. 49,747. (No model.)

To all whom it may concern:

Be it known that I, EDWARD A. JOHNSTON, a citizen of the United States, residing at Chicago, county of Cook, State of Illinois, have 5 invented certain new and useful Improvements in Self-Binders; and I do hereby declare the following to be a full, clear, and exact description of the invention, such as will enable others skilled in the art to which it 10 appertains to make and use the same.

The invention relates to self-binders for grain and corn harvesters and the like, and has to do more especially with the devices for forming and compressing the bundle.

15 The particular object in view is to provide improved means for holding the compressor-finger up above the deck during the formation of the bundle and operating it, so as to give the final compression at the time when 20 the knot is being tied and to drop out of the way below the deck when the bundle is ready to be discharged. In the preferred arrangement herein illustrated the compressor-finger is pivoted eccentrically to the needle, and the

25 shaft of the needle has hung on it a latch which is operated at appropriate periods, so as to throw up the compressor and lock it in its raised position independently of the needle. Just before the needle descends this 30 lock is broken or released and the compressor falls of its own weight, quickly clearing the way for the discharge of the bundle; but immediately on the release of the lock, just before the knot is completed, a cam on the needle

35 strikes a projection on the compressor-arm, thereby throwing the latter momentarily still farther up, so as to give an additional squeeze to the bundle for the purpose of slackening the band and preventing the action of 40 the knotter from breaking the twine by allowing it to draw extra twine from the band encircling the bundle. As the compressor moves up to give the bundle this final compression the latch, being released, falls; but

45 the compressor does not fall with it, but is held up by the needle-cam until the needle has receded slightly, when it is released and allowed to drop. The descent of the needle then continues, and after the bundle has been 50 discharged from the machine it picks up the latch again and causes it to reengage the com-

pressor-arm and raise and restore it to its elevated position, with the compressor-finger projecting above the deck. In this position the latch is locked, and the needle is free to 55 rise and perform its original functions up to the point where the tying of the knot is completed, and the bundle is ready to be discharged when the lock is broken and the compressor released and dropped in the manner 60 above described.

In the accompanying drawings, forming part of this specification, Figure 1 is a side elevation of the needle and compressor in their normal positions ready to receive the incoming bundle, the position of the parts in giving the final compression to the bundle being indicated in dotted lines. Fig. 2 is a similar view of the same parts in the positions occupied after the release of the latch and just before the compressor falls. Fig. 3 is a similar view showing the compressor dropped below the deck and the needle receding. Fig. 4 is a view similar to Fig. 3, but with the needle lowered still farther, illustrating the operation of the latch in restoring the compressor-arm into the position shown in Fig. 1.

Referring to the views, *a* denotes the needle or binder arm, and *b* the compressor-finger. The needle is secured to the shaft *a'*, 80 and the compressor-finger is adjustably mounted on the arm *b'*, which is pivoted eccentrically to the needle-shaft on a shaft *b''*.

Freely pivoted on the needle-shaft *a* alongside the hub of the needle is a latch or dog *c*, 85 and on the heel of this latch is a projection *c'*, the purpose of which will be explained farther on. The compressor-arm *b'* has a projection *b''*, carrying a friction-roller *b'''*, and the latch *c* extends upward from the needle-shaft sufficiently to engage the roller on the projection *b''*, as illustrated in Fig. 4, and lift the compressor-arm and its finger from the position indicated in Fig. 3 to that shown in Fig. 1. The hub of the needle is provided 90 on the side adjacent to the latch *c* with projections *a''* and *a'''* for the purpose of coöperating with the projection *c'* on the latch and causing it to rise and fall at the proper periods and lift the compressor-arm and to release it and allow it to fall. As the latch is 100 operated only when the needle is approach-

ing the extremes of its movement, the projections a^2 and a^3 are spaced apart on the hub of the needle sufficiently to permit the required movement. The projection a^3 engages 5 the upper side of the projection c' as the needle descends, as illustrated in Figs. 3 and 4, and lifts the latch from the freely pendent position shown in Fig. 2 to the elevated position illustrated in Fig. 1. In moving up the latch 10 engages the under side of the roller b^5 and lifts the compressor-arm, and when the arm has been lifted to its highest point the end of the latch slips past the roller and engages the shaft on which the compressor-arm is pivoted, 15 thereby limiting the further upward movement of the latch, and in order to provide a lock for the compressor-arm the forward end of the latch is slightly recessed or curved to conform approximately to the shape of the 20 roller b^5 , so that when the point of the latch passes the roller the latter will settle into the recess in the end of the arm and form, in effect, a toggle-lock, holding the compressor rigidly in its elevated position. When the 25 needle rises and just before it reaches the upward limit of its movement, the projection a^2 on its hub strikes the under side of the heel projection c' of the latch and breaks this lock by knocking the front end 30 of the latch out from under the roller b^5 , and the latch is then allowed to fall into the position indicated in Fig. 2. It is necessary, however, that the compressor should not fall immediately, and, moreover, it is desirable 35 that it be given a further slight elevation before it is allowed to fall in order to compress the bundle still further during the tying of the knot, so that there may be sufficient slack in the band to prevent the tier-bill from 40 breaking the twine. For this purpose the hub of the needle is provided with a tailpiece having a lug or projection a^4 , and the compressor-arm is provided with an inward projection b^4 , extending toward the hub of the 45 needle, on which projection there is preferably sleeved an antifriction-roller b^6 . When the compressor-arm is in its normal elevated position, this roller stands in the path of the projection a^4 , and as the needle reaches the 50 upward limit of its movement and just after the projection a^2 has struck the heel projection c' of the latch, and thereby broken or released the lock holding the compressor up, the heel projection a^4 on the needle engages 55 the roller b^6 on the compressor-arm and not only prevents the arm from falling, (which it otherwise would do immediately on the release of the latch,) but raises the arm and its finger b farther upward into the position indicated in dotted lines in Fig. 1 and in full lines in Fig. 2, thereby giving to the bundle the additional final compression above described. Immediately after this final compression of the bundle the needle starts to 60 recede and the roller b^6 runs off the lower edge of the projection a^4 , and the compressor-arm, being thereby deprived of all support, falls of 65

its own weight, the roller b^6 passing upward between the projection a^4 on the heel of the needle and the hub of the latch c , as clearly 70 indicated in Fig. 3. The needle continuing its descent, the projection a^3 strikes the heel projection on the latch and swings the front end of the latch upward, causing it to engage the roller b^5 on the compressor-arm and lift 75 the arm and its finger, as clearly indicated in Fig. 4, until the needle has reached the lower limit of its movement, when the front end of the arm engages the under side of the shaft b^2 and the parts are locked in the position indicated in Fig. 1, as heretofore described. 80

Having thus described the invention, what I claim, and desire to secure, is—

1. In a self-binder, the combination of a 85 compressor-arm pivoted relatively eccentrically to the needle, a latch pivoted concentrically to the needle to hold the arm in elevated position, and projections on the needle to engage and release the latch when the needle rises and allow the compressor to fall, and to 90 raise the latch and cause it to lift the compressor when the needle falls.

2. In a self-binder, the combination of a pivoted compressor-arm, a pivoted latch to hold the arm in elevated position, a connection 95 between the needle and the arm to give a final compression to the bundle, and a connection between the needle and the latch whereby the latter is caused to lift the compressor when the needle descends, and is released to allow the compressor to fall when the needle ascends. 100

3. In a self-binder, a pivoted compressor-arm, a pivoted latch, a projection on the heel of the compressor-arm, a cam on the needle 105 co-operating therewith to give a final compression to the bundle, a projection on the compressor-arm engaged by the latch, and co-operating projections on the needle and latch to raise the latter and cause it to lift the compressor. 110

4. In a self-binder, the combination of a compressor-arm pivoted eccentrically to the needle, a latch freely pivoted on the needle-shaft, a projection on the arm to be engaged by the forward end of the latch, a projection on the heel of the latch, and projections on the needle to engage the latch projection when the needle is raised for the purpose of releasing the latch and allowing it to fall, and lifting it when the needle descends and causing it to raise the compressor. 115 120

5. In a self-binder, the combination of a pivoted compressor-arm, a latch freely pivoted on the needle-shaft and having a heel projection, a projection on the compressor-arm to be engaged by the forward end of the latch, projections on the needle to engage opposite sides of the heel projection of the latch as the needle rises and falls, a projection on the heel of the compressor-arm, and a cam on the needle to engage the latter and give the bundle a final compression after the latch is released. 125 130

6. In a self-binder, the combination of a pivoted compressor-arm, a pivoted latch to lift and hold the arm in elevated position, a projection on the latch, a projection on the needle 5 to engage the upper side of the latch projection as the needle falls to lift the latch, a projection on the needle to engage the under side of the latch projection as the needle rises to release the latch, and a cam on the needle to 10 catch the compressor-arm when released by the latch to hold it until the needle starts to recede.
7. In a self-binder, the combination of a pivoted compressor-arm having a projection 15 b^3 , a freely-pivoted latch having its front end c^2 constructed to fit the projection b^3 , a projection c' on the heel of the latch, and a needle having the projection a^3 to engage the latch projection c' .
8. In a self-binder, the combination of a 20 compressor-arm pivoted upon a shaft b^2 , a pivoted latch having a heel projection c' , a projection a^3 on the needle to engage the projection c' and lift the latch, and a projection b^3 on the compressor-arm to be engaged by 25 the front end of the latch, the needle projection a^3 serving to lift the latch and raise the compressor-arm until the projection b^3 runs off its end, and the shaft b^2 serving to limit the upward movement of the latch after it 30 has passed the projection b^3 , thereby forming a toggle-lock to hold the compressor up.

In testimony whereof I affix my signature in presence of two witnesses.

EDWARD A. JOHNSTON.
